UNITED STATES PATENT OFFICE.

WILLIAM M. JENKINS, OF MINNEAPOLIS, MINNESOTA.

PUMP JACK.

Application filed May 27, 1925. Serial No. 33,163.

This invention relates to driving mechanism for pumps commonly known as pump jacks, and especially to that type of pump jacks employing a reciprocating lever driven 5 from a rotary gear.

It is an object of the invention to provide an extremely simple but highly efficient pump jack comprising a minimum number of parts and of exceptionally strong and 10 durable construction.

It is an additional object to provide a pump jack having a reciprocating lever, which lever is driven in its lifting stroke at slower speed and with a greater transmission 15 of power than in its downward stroke, thereby speeding up the action of the pump and giving the greatest power where it is needed in lifting the water.

Another object of the invention is to provide 20 a pivoted reciprocating lever having secured thereto an arcuate or concavo convex internal gear engaged by a pinion rotating on a fixed axis, the concave and convex sides of said gear being disposed substantially concentric with the pivot point of said lever.

A still further object is in such a device to provide means in the form of a cam guide-way concentric with the concavo convex 30 internal gear for properly guiding the gear in its traveling movement about the driving pinion, holding said parts in proper engagement at all times.

An additional object of the invention is to provide 35 in such a pump jack a closed casting for all the working parts in which an oil receptacle is provided adapted to supply oil through the movement of the reciprocating lever to all of said parts.

Another object of the invention is to provide 40 a reciprocating lever slidably pivoted adjacent one end thereof and carrying a concavo convex internal gear rigidly secured adjacent the other end, in mesh with a pinion rotating on a fixed axis, the slidable pivot of said lever permitting the ends of said gear to be moved around said pinion, whereby 45 said pinion may engage the opposite side of said gear, and, in such a slidable pivotal connection, to provide means for varying the normal pivot point of the lever whereby 50 the length of the stroke of said lever may be considerably varied.

These and other objects may be apparent 55 from the following description made in connection with the accompanying drawings,

wherein like characters refer to like parts throughout the several views, and, in which,

Fig. 1 is a side elevation of the pump jack, some portions of the casing being broken 60 away, and others shown in section;

Fig. 2 is a horizontal cross section of the same taken on the line 2—2 of Fig. 1;

Fig. 3 is a diagonal cross section taken on the line 3—3 of Fig. 1; and 65

Fig. 4 is a vertical cross section taken on the line 4—4 of Fig. 1.

In the drawings, a closed casing is illustrated in which the working parts are disposed, said casing comprising a pair of preferably cast shell-like sections 5 and 6, respectively, having the base flanges 5^a and 6^a, respectively, provided with apertures through which bolts 7 may be passed to secure the casing to a suitable support. The 70 two shell sections 5 and 6 are also provided with outwardly projecting flanges 5^b and 6^b, respectively, which are bolted together to form the closed casing. The lower portion of the casing adjacent the base forms a receptacle 8 adapted to contain oil for the lubrication of the working parts of the jack. 75

A vertical slot 9 is formed in the front wall of the casing, through which the working end of a reciprocating lever 10 is adapted to be swung. The lever 10 is provided at its inner end with a bearing slot 10^a. Oppositely aligned adjustment slots 11 are formed in the sides of sections 5 and 6, respectively, and a nutted bolt 12 is passed through said 80 adjustment slots 11 through the bearing slot 10^a of the lever, thereby slidably pivoting said lever to the casing. The bolt may thus be rigidly clamped in a desired transverse position in slots 11, thereby determining the 85 pivot point of lever 10. Obviously, this pivot point may be varied by the position of bolt 12 in slots 11 from the outside of the casing. Bosses 11^a are projected on the inner sides of sections 5 and 6 of the casing in horizontal alignment, and adapted to form bearing surfaces for the pivoted end of lever 10. 90

A bearing 13 is provided in the section 6 of the casing adjacent the front end thereof, and substantially in horizontal alignment with the adjustment slots 11, and a transverse shaft 14 is journaled in bearing 13 carrying outside the casing the pulley 15 connected by an endless belt 16 to a motor or other source of power 17. On the inner end of shaft 14, a relatively small pinion 18 is keyed or otherwise rigidly secured, prefer- 100 105 110

ably being disposed centrally and longitudinally of the casing. It will be noticed that the inner end 14^a of shaft 14 is extended somewhat beyond the pinion 18, the purpose of which will presently be explained.

The lever 10 has a relatively large, preferably elliptical shaped head or plate portion 10^b vertically disposed adjacent its outer end and the front end of the casing. Rigidly secured to the enlarged head 10^b of the reciprocating lever, is a concavo convex or arcuate internal gear 19 having its concave and convex sides disposed substantially concentric with the normal pivot point of lever 10. A concavo convex shaped flange 19^a, corresponding with the gear 19, is secured to the outer surface of said gear and engages the outer side of the pinion 18, thereby holding gear 19 to said pinion. A guideway or cam 20, also of concavo convex shape, is formed in the enlarged head 10^b, extending within and concentric to the gear 19. Pinion 18 is disposed within the sides of gear 19 engaging the same, and the projecting end 14^a of the rotary shaft 14 is seated in the cam or guide 20, thereby maintaining the proper engagement between pinion 18 and gear 19 at all times during the movement of the latter. Outturned arms 21 are rigidly secured to the free end of lever 10 on the outer side of the slot 9. A pair of pitmen 22 are pivoted to said arms adapted to actuate the pump piston through the reciprocation of lever 10. A transverse outwardly extending collar 23 is formed on the lever 10 between the enlarged head 10^b and the outer end of the said lever adjacent the inner side of slot 9, which collar is adapted to prevent oil from running down lever 10 and out of the casing through slot 9. The collar 23 thus catches any oil traveling down the lever and drops the same back in receptacle portion 8 of the casing. A gasket 24 is interposed between the two lower portions of the sections 5 and 6, when the same are secured together, thereby making a liquid tight joint in the receptacle part of the casing.

Operation.—Assuming the pitmen 22 to be directly connected to the piston of the pump, when a clockwise rotation is transmitted to the shaft 14, the pinion 18 will cause the gear to move therearound in an arcuate concavo convex path, thereby reciprocating lever 10. It will be obvious that, in the upstroke or lifting stroke of lever 10, the concave or longer side of gear 19 will be engaged, said side of said gear being of greater radius than the convex or shorter side. Consequently, a greater gear reduction will exist when said concave side of the gear is engaged, thereby giving the lifting stroke of the lever greater power and less speed than the down stroke. Increased power is, therefore, provided in the lifting stroke where it is most needed, while the plunger of the

pump will be reciprocated downwardly at faster speed where little power is needed.

By unloosening the nut on bolt 12 and rigidly setting it to a desired transverse position in the slots 11, the radius of the reciprocating lever 10 may obviously be varied and the stroke of the lever consequently changed within certain limits. Obviously, this adjustment may be made from the outside of the casing, either when the device is idle or when the device is in operation. The length of slots 10^a and 11, of course, determine the limitation of this adjustment in the length of the stroke of the lever.

It will be noticed that the lower end of the enlarged head 10^b carrying the arcuate internal gear, at each down stroke of the lever, is immersed in the oil carried in receptacle 8 of the casing, and that small amounts of this oil will be carried to the pinion on each up-stroke of the lever and will also run down the main portion of the lever 10 to the pivot bolt 12 and the slide bearing 10^a, thereby lubricating all working parts of the device. As has been stated, the oil will be prevented from running down the outer end of the lever and out of the casing by means of the outwardly extending collar 23.

From the above description, it will be seen that applicant has invented a pump jack comprising very few parts, but operating efficiently for all purposes intended. The device has been put to actual usage and has been found highly successful for the purposes enumerated.

In several States, laws have been enacted requiring all working machinery to be covered or have the moving parts thereof guarded or covered for the protection of the public. Applicant's device provides a pump jack having all of its working parts housed within a casing, and thereby complying with the laws of these States.

It will, of course, be understood that various changes may be made in the form, details, proportion and arrangement of parts without departing from the scope of the invention.

What is claimed is:—

1. A pump jack having in combination a frame having spaced sides, a lever or walking beam mounted within said frame, and having its inner end slidably pivoted to the sides of said frame, a concavo-convex gear rigidly carried at one side of said lever, a pinion journaled in one side of said frame, and engaging said gear to oscillate said lever, means connected to said pinion and co-operating means carried by said gear adapted to maintain the engagement between these parts, and means for connecting said lever with a pump plunger.

2. A pump jack having in combination an upright casing, having a substantially vertical slot in one edge thereof, a lever or

walking beam mounted within said casing and having its free end working through said slot, the inner end of said lever being pivoted to said casing, a concavo-convex gear rigidly carried at one side of said lever, a pinion journaled in said casing and engaging said gear to oscillate said lever, means for affording said gear horizontal motion relative to said pinion, means for maintaining the engagement between said pinion and gear, and means for connecting the free end of said lever with a pump plunger.

3. A pump jack having in combination an upright casing, a walking beam pivoted within said casing and having its free end working through said casing, a concavo-convex internal gear rigidly carried at one side of said lever, a horizontally disposed stub shaft journaled in one side of said casing adjacent said gear, a pinion rigidly secured to said stub shaft within said casing engaging said gear, a guide adjacent said gear in which the inwardly projecting end of said stub shaft is seated, adapted to maintain the engagement of said gear and pinion and means for connecting said lever with a pump plunger.

4. A pump jack having in combination a frame having a bearing slot therein, a lever having a bearing slot adjacent one end thereof, an adjustable pivot member passing through said slot in said lever and adapted to be secured to said frame in various positions relative to said slot in said frame, a concavo convex gear mounted on said lever, a pinion journaled in said frame engaging said gear, and means for maintaining the engagement of said gear and pinion.

5. A pump jack having in combination an upright hollow casing or frame having a vertical slot through one end thereof, a lever pivoted within said casing and having

its free end working through said slot, a driving shaft journaled in said casing, a pinion rigidly secured to the inner end of said shaft within said casing, and a gear on said lever engaging said pinion operative to reciprocate said lever when said shaft is rotated, the lower portion of said casing constituting a receptacle adapted to contain a lubricating fluid, whereby said gear will be immersed into said fluid when said lever is reciprocated and said pinion and pivot of said lever will be subsequently lubricated.

6. The structure set forth in claim 5, and said lever having a flange on the outer side of said gear adapted to prevent lubricating fluid from flowing down said lever to the outer side of said casing.

7. A pump jack having in combination a hollow casing having a slot through one end thereof, a lever disposed for the most part within said casing and slidably pivoted thereto but having one of its ends working through said slot, a concavo convex internal gear rigidly carried by said lever and disposed within said casing, a transverse horizontal shaft journaled in said casing, a pinion rigidly carried by the inner end of said shaft and engaging said gear, projecting means carried by said shaft in alignment therewith and a guideway concentric with said gear in which said projecting means is seated, whereby said pinion will be held in engagement with said gear and said lever will be reciprocated when said shaft is continuously turned in one direction.

8. The structure set forth in claim 7, and said hollow casing having its inner lower portion in the form of a receptacle adapted to contain oil whereby said gear, pinion and pivot member of said lever may be oiled when said lever is reciprocated.

In testimony whereof I affix my signature.
WILLIAM M. JENKINS.
